S. O. Palmer (assignor to J. F. Seymour) Utica, N.Y.
Letters Patent. (Design No. 94) dated, October 10th (1841)

The schedule referred to in these Letters Patent and making
part of the same.

To all whom it may concern; Be it known, that I, Lucius O. Palmer of the City of Utica in the County of Oneida, and State of New York, by my own industry genius and expense have invented and produced a new & original Design, shape, configuration, and Pattern of Stone plates to be used in the manufacture of stoves.

The nature of my invention consists in the peculiar shape, configuration, and ornamental carved work of the outer surface of the cast iron plates forming the stove which is in the form of an elevated box of cast iron. And I do hereby declare the following as exact description thereof as can be given reference being had to the annexed drawing as part of this specification. The outer surface of the plates consists of Gothic columns, each column being composed of three shafts united, and on these columns rest Gothic arches; between the columns are represented trellises with leaves and fruit of grape vines running up behind them; and between & over the arches is also a representation of the leaves and fruit of Grape vines. The front and back plates are alike excepting that the flue or pipe hole is placed in the back plate; and the side plates are alike excepting that a circular damper for closing and regulating the draft is introduced into the right-hand plate, and also the door. The box stands on an oblong hearth of fanciful shape, the outer edges consisting of curved lines, and with an embossed edging, and a raised carved ornament in front of the space between the two central columns, which cannot be more particularly described by words, but is accurately represented by the drawing thereof hereto annexed; the sides and plates of the stove all curve outward gradually as they rise towards the top, the curve commencing at the top of the Gothic columns. The outer edge of the top is surrounded with a perfectly plain, round moulding, within which is a flat surface; from this flat surface the top is raised for the space of about two inches, when it again becomes flat leaving a level space on the top in the shape of a parallelogram & the two inches of raised work before men-

timed are ornamented with fanciful carved work, which cannot be described but will be seen by reference to said annexed drawing. The stone rests on four legs, ornamented with embossed carved work, for a more particular description of which, I refer to the said annexed drawings. What I claim as my invention and desire to secure by letters patent is the design, shape, configuration, style, and ornamental carvings of the external ^{of the pedestal} surface, of the stone.
